UNITED STATES PATENT OFFICE.

ADOLPH PETZOLD, OF PHILADELPHIA, PENNSYLVANIA, ASSIGNOR TO JOHN BROMLEY & SONS.

DESIGN FOR A RUG.

SPECIFICATION forming part of Design No. 19,940, dated June 24, 1890.

Application filed May 31, 1890. Serial No. 353,861. Term of patent 3½ years.

To all whom it may concern:

Be it known that I, ADOLPH PETZOLD, a citizen of the United States, and a resident of the city of Philadelphia, State of Pennsylvania, have invented a certain new and original Design for a Rug, of which the following is a specification, reference being had to the accompanying drawing, forming a part hereof.

My invention has relation to a design for the surface ornamentation of a rug, and will be fully understood by any one skilled in the art of weaving rugs by reference to the accompanying photographic illustration, which is a view of the rug design as I prefer to use it. It is divisible, however, into two parts A and B, on the line *a b*, as respects the central portion of the figure within the rectangular lines inclosed within the border. The parts above and below the line *a b* within said

rectangular lines, respectively, may be "repeated," or substituted each for the other, without departing from the general plan of the design, but as a modification of the design as a whole, as shown in said illustration hereto annexed.

I claim—

1. The design for a rug, substantially as shown and set forth.
2. The design for a rug, consisting of the part A repeated, substantially as set forth.
3. The design for a rug, consisting of the part B repeated, substantially as set forth.

In testimony whereof I have hereunto affixed my signature this 22d day of May, A. D. 1890.

ADOLPH PETZOLD.
